BUILDING HEATING

Albert F. Bemis, Newton, Mass., assignor to Bemis
Industries, Incorporated, Boston, Mass., a cor-
poration of Delaware

Application August 5, 1931, Serial No. 555,312

9 Claims. (Cl. 237—69)

This invention relates to an improved heating system for buildings such, for example, as dwelling houses, and more particularly to arrangements adapted to employ radiant heat for heating building interiors.

Conventional heating systems are unsatisfactory, since they involve the concentration of heat into limited regions and depend upon uncertain convection currents for the dissemination of the heat to the various portions of a room. This results in an uneven heating and the collection of hot air adjoining the ceiling where it has little effect in properly heating the occupants of the room. Such heating systems necessitate a relatively high temperature in order to permit the occupants of the room to be comfortable and consequently result in an abnormally low relative humidity, a condition which generally is recognized as having an injurious effect upon health and house furnishings. These conventional heating systems furthermore are relatively inefficient due to the unnecessarily high temperatures which they require and the dissipation of the heat which collects at the upper portion of a room.

It is a primary object of the present invention to obviate the deficiencies in conventional heating systems and to provide substantially uniform heating of all portions of a room, while avoiding unnecessarily high temperatures and thus permitting a materially higher normal moisture content of the air within the room than is possible with the conventional heating arrangements. Furthermore, the present invention avoids the employment of exposed unsightly heating elements such as radiators, with their propensity to collect dust, and by convection to deposit smudges on the walls directly thereabove, and also avoids the employment of open registers and the like with the attendant objections from the point of view of sanitation and appearance.

To obtain these desirable results, I preferably provide a substantially continuous layer of heat conductive and radiant material upon all sides of the room, including the floor and ceiling. Radiant heat may be effective in maintaining the bodies of occupants of a room at a satisfactory temperature while the air of the room itself may be materially cooler than where convection heat is primarily depended upon. In other words, radiant heat rays, upon striking the body of an occupant of the room, will raise the temperature of the body surface by a substantially greater amount than they will raise the temperature of

the air through which the rays pass. Accordingly the body surface may have a temperature equal to that which it would possess were the air of the room heated to a materially higher temperature and primarily depended upon to heat the body of the occupant, as is the case with present conventional heating systems. Since this invention permits the air in the room thus to remain at a temperature lower than is conventional, its moisture content and relative humidity may be substantially higher and the conditions within the room are therefore more healthful than with ordinary heating arrangements that depend primarily upon heating the air within the room to a temperature conducive to the comfort of its occupants.

In order to permit the effective employment of radiant heat in this manner, it is necessary to avoid concentration of the source of heat in a limited region or regions in the room and to distribute the source of radiant heat so that the intensity of the emanated rays within the room will be substantially uniform. It is therefore advantageous to arrange the heating means so that the radiant heat rays emanate from substantially all of the wall surfaces of the room, these wall surfaces having a temperature which is not greatly above that of the interior of the room in contrast to the relatively high temperature which accompanies the use of steam radiators or the like.

Preferably the primary source of heat supply is disposed adjoining the floor of the room, for example, either below the floor, or within the floor assembly. This arrangement is highly advantageous when heat conductive, radiant sheets such, for example, as metal plates or panels are disposed in the walls of a room, since the conductivity of these wall sheets is effective in permitting the heat to be conducted to the upper parts of the walls and to be radiated from the same, even though a somewhat greater proportion of heat may radiate from the lower parts of the walls and from the floor. Accordingly, this arrangement permits the radiant heat to co-operate with the limited convection currents, which are present under ordinary circumstances, to cause substantially uniform heating of all parts of the room so that the temperature adjoining the floor and that adjoining the ceiling may be substantially the same, thus avoiding the losses and overcoming the disadvantages which are characteristic of the conventional heating systems which depend primarily upon convection currents and involve the maintenance of the air

- within the room at an unduly high temperature. Furthermore, the arrangement of the primary heating elements in or adjoining selected parts of the room, such as the floor or below the same, 5 not only avoids relatively low temperatures of the air adjoining the floor, but also has distinct structural advantages in that both the original installation and subsequent servicing is greatly facilitated.
- 10 In accordance with this invention structural frame elements, for example, vertical elements corresponding to studs and posts, and horizontal elements corresponding to girts and joists may be formed of heat conductive material, i. e., 15 metal, and may not only act as structural portions of the building but also be effective in properly conducting and distributing heat to the radiating elements or units which may be in the form of metal sheets. More particularly for this 20 purpose I prefer to employ units having marginal channels and opposite face sheets of conductive material, such as metal. Such units may be disposed vertically to provide the vertical walls and horizontally to provide the floors and ceilings.
- 25 The specific structural arrangement of one form of these units and the cooperating girts, horizontal frame members, and adjuncts are described and claimed in my copending application, Serial No. 553,033, filed July 25, 1931, Patent 30 No. 1,958,124, May 8, 1934, which is incorporated herein by reference. Preferably, the face sheets of the units provide substantially continuous metallic wall surfaces which define the faces of the walls of rooms and provide large radiating surfaces, for example, these surfaces may comprise 35 the major portions of the wall surfaces for the rooms.

Further objects and advantages will be apparent from a consideration of the following description and accompanying drawings which exemplify, somewhat diagrammatically, one embodiment of this invention chosen for the purpose of illustration.

In the drawings:

- 45 Fig. 1 is a diagrammatic sectional elevation showing the interior structure of a building embodying my novel heating system;
- 40 Fig. 2 is a horizontal section of the building;
- Fig. 3 is a vertical section through a portion of 50 the first floor;
- Fig. 4 is a perspective view of a floor and ceiling unit;
- Fig. 5 is a vertical section showing a modified 55 arrangement of the heating elements; and
- Fig. 6 is a vertical section showing a modified type of floor unit embodying an electric heating element.

Referring to the drawings, and more particularly to Figs. 1 and 3, the numeral 1 designates 60 the outer walls of the building which may be formed of any suitable jacketing material, such as concrete, resting upon a suitable foundation which also carries concrete posts 2 supporting the sills 3. Interposed between the concrete 65 jacket 1 and the vertical frame members is a layer of heat insulating material 4 of any suitable type such, for example, as felted fibrous material, or mineral wool.

The vertical frame members or units 5 are 70 disposed about the interior of the building as shown in Figs. 1 and 2, being secured in position by any suitable means, and together with the horizontal frame members 3 and 6 define the various rooms of the building. Preferably the 75 vertical members or wall units 5 comprise simi-

lar spaced rectangular metal sheets 10 and 11 having their edges connected by channel irons 12, thus providing closed metal boxes or units having grooved or recessed edge portions and face plates which define the surfaces of the vertical walls of the rooms. The horizontal frame members 6 preferably comprise channel 7 secured to the opposite sides of a web plate 8 to provide flanged portions which interfit with the recessed portions of the unit 5, as shown in Figs. 10 1 and 3. The web plate 8 projects beyond the channel or angles 7 to provide supports for the floor and ceiling units 15.

The units 15 are similar to the wall units and comprise similar spaced metal face sheets 15 16 and 17 which preferably are rectangular and which have their edges connected by four channel irons 19 cooperating with the face sheets in providing a substantially closed metal box or unit. As shown in Fig. 4 the upper face sheet 20 17 may have a greater area than the lower sheet to provide overhanging end portions for connection to the girts 3 and 6. Preferably, as shown in Figs. 2 and 3, a plurality of these units extend across the room and are disposed in side 25 by side juxtaposition to provide a substantially continuous floor surface, and in like manner a plurality of similar panels extend across the upper part of the room to provide the ceiling. In both the floor and ceiling units the longitudinal 30 channels possess sufficient strength and rigidity to serve as floor joists, and likewise, the corresponding elements of the wall panels 5 serve as the studs and posts of the structure. It is thus evident that the wall, ceiling and floor units 35 not only include the structural frame elements of the assembly, but also provide substantially continuous radiating surfaces which define a major portion of the wall surfaces of the room. Suitable metal elements such as angles 20 may 40 be employed to connect the floor and ceiling units 15 to the wall units 5 and similar angles 21 may be employed between the wall units and the girts 6 (as shown in Figs. 1, 3, 4 and 5), thus providing excellent heat conductors between the units and the girts.

Suitable heating elements such as steam coils 30 may be disposed below the floor units 15, as shown in Figs. 1 and 3, and heat insulating material 33 is preferably disposed below the heating 50 coils 30 so that the major portion of the heat therefrom is transmitted to the floor units 15 and the adjacent portions of the girts and wall units. As the wall, ceiling and floor units are disposed in heat transfer relation to, or thermal 55 association with, both the girts 3 and 6 and the heating elements 30, it is apparent that part of the heat from the coils will be transmitted directly to the floor units while a substantial part will be transmitted to the girts 3 and 6, the wall 60 units 5, and ultimately to the ceiling units. The heat thus transmitted is conducted to the face sheets of the different units and emitted therefrom to the interior of the rooms by radiation.

If desired, heating coils 50 may be disposed 65 in the channels adjoining the floor and ceiling units 15 above the rooms of the first floor, thus aiding the heating of the upper portions of the rooms on the lower floor as well as the rooms in 70 the second story.

Obviously, the lower parts of the face sheets of units 5, particularly in the upper story, may normally be warmer than their upper parts, and accordingly a greater amount of heat will be 75 radiated therefrom. However, an appreciable

amount of heat will be conducted to the upper portion of the units by means of the channels and face sheets, and ultimately to the ceiling units by means of the angle irons 21. As the 5 wall units are hollow and have substantially dead air spaces, the air within these units will become heated and cause convection currents to be set up which will aid the transmission and distribution of heat to the upper parts of the 10 wall units and to the ceiling units. Furthermore, the insulating wall 4 confines the heat transmitted to the girt 6 to the vicinity of the wall units, thus effectively preventing its dissipation and aiding its transmission to the upper 15 floors of the building.

In the optional arrangement shown in Fig. 5 the heating coils 40 are disposed between the channels connecting the face plates of the lower floor units and the vertical frame members or 20 wall units. Both the floor and wall units are disposed in close thermal association with the heating element and receive heat directly therefrom and transmit the same to their face sheets from which the heat will be emanated to the 25 interior of the rooms by radiation.

In the modification shown in Fig. 6, the floor units 45 are provided with an electric heating element 150 from which heat is transmitted to the different units and frame members in the 30 manner previously described.

In all of the illustrated embodiments of the invention, it is evident that the heating arrangement causes a somewhat greater radiation of heat to the lower parts of the room and due 35 to the limited convection currents which are usually present, a certain amount of heat will ascend to the upper part of the room and will result in the substantially uniform heating of all parts of the room. It will be noted that the 40 arrangement of the upright units with their inner and outer face sheets and channels is effective in permitting the transmission of heat to the upper part of the wall units and to the ceiling panels so that an objectionable proportion 45 of the total radiation will not emanate from the lower portions of the wall units.

Furthermore, it is evident that the structural portions of the building which support the various loads, such as for example those imposed 50 upon the various floors, are also effective in conducting and distributing the heat. Accordingly the marginal channels of the units as well as the horizontal frame members or girts are not only effective as structural members but as 55 heat transmitting elements.

It will, of course, be understood that the accompanying drawings particularly illustrate an arrangement of elements for building heating purposes, and that the illustrations are purely 60 diagrammatic in character, various details such as specific fastening means, door and window arrangements, etc. not being shown in detail in this application, but being fully illustrated in my copending application identified above.

65 I claim:

1. Building structure of the class described comprising metal wall, floor and ceiling sheets, the floor and ceiling sheets, affording substantially continuous metallic surfaces with an area substantially coextensive with the area of a 70 room, the wall sheets being in heat conductive relation to the floor and ceiling sheets, and heating elements associated with said sheets adjoining the lower part of the room, whereby the 75 interior of the room may be heated by heat

radiation from all of said sheets, the temperature of the sheets adjoining the lower part of the room being greater than that adjoining the upper part so that the interior of the room is also heated by convection currents. 5

2. Building structure of the class described, comprising metal wall units, metal ceiling sheets, the wall units providing a substantially continuous metal surface on one side of a room, the ceiling sheets being in heat conductive relation 10 to the wall units, the wall units comprising spaced inner and outer metal sheets with metal conductors connecting their edges, and heating means associated with the lower parts of the wall units. 15

3. A building structure of the class described comprising metallic frame members defining the rooms of the building, heating units comprising metal face plates, said units being directly supported by and thermally associated with said frame members, said face plates defining a major portion of the surfaces of the walls of said rooms, and heating elements theremally associated with said frame members whereby heat is transmitted to said frame members and 20 thence to the heating units and emitted from said units to the interior of the rooms by radiation. 25

4. A building structure of the class described comprising vertical walls defining the exterior 30 of the building, metallic frame members joined to each other and defining the rooms of the building, insulating material interposed between the frame members and said vertical walls, heating units supported by and thermally associated 35 with said frame members, said units comprising metal face plates defining a major portion of the wall surface of said rooms, and heating elements thermally associated with said frame members whereby heat is transmitted thereto and emitted 40 from the face plates of said units to the interior of the rooms by radiation. 45

5. A building structure of the class described comprising metallic frame members defining the rooms of a building, heating units supported by 45 and thermally associated with said frame members, said units comprising metal wall, floor and ceiling plates defining a substantial portion of the surface of said rooms, and heating elements disposed below the floor plates in close proximity 50 to adjacent portions of said frame members, whereby heat is transmitted to frame members and heating units and emitted from the plates of said units to the interior of the rooms by 55 radiation. 55

6. A building structure of the class described comprising horizontal metallic frame members, floor and ceiling heating units supported thereby and thermally associated therewith, vertically disposed members constituting the vertical frame 60 members of the structure and the wall heating units, said units each comprising spaced metal plates having their marginal portions connected by channel irons to provide closed metal chambers, said heating units defining a substantial portion of the surfaces of the rooms of the building, and heating elements disposed below said 65 floor heating units in close proximity to the horizontal frame members and the end portions of said vertically disposed members, whereby heat 70 is transmitted thereto and emitted from said units to the interior of the rooms by radiation. 75

7. A building structure of the class described comprising vertical walls defining the exterior 75 of the building, horizontal metallic frame mem-

- bers, vertically disposed members constituting the vertical frame members and the wall heating units, insulation interposed between said latter members and the vertical walls of the building,
5 said vertically disposed members comprising spaced sheet metal plates, channel irons forming the vertical frame members and connecting the vertical margins of the plates to provide closed metal chambers, floor and ceiling heating units
10 supported by and thermally associated with said horizontal frame members, said heating units defining the rooms of the building, and heating elements disposed below said floor units in close proximity to said frame members, whereby heat
15 is transmitted thereto and emitted from said units to the interior of the rooms by radiation.
8. A building comprising side walls having inside faces formed of metal plates, floors comprising horizontal metal parts in heat transfer
20 relation to said plates, and means associated with

the floors for heating the rooms by conduction through said floor parts and radiation through said wall plates.

9. Building structure of the class described comprising horizontal metal frame members, floor members extending between horizontal frame members, box-like wall units having inner face sheets defining the vertical walls of rooms, the frame members having parts in interfitting engagement with the upper and lower ends of 10 the wall units, and heating means disposed adjoining the floor and thermally associated with the horizontal frame members supporting the floor, whereby heat is conducted to the wall units and is radiated from the inner surfaces of the 15 latter into the room while localized convection currents may cause the internal flow of heat within the individual units.

ALBERT F. BEMIS. 20
